CLAIM

The ornamental design for dumbbell shaped surveillance camera and infrared sensor, as shown and described.

DESCRIPTION

FIG. 1 shows a perspective view of a dumbbell shaped surveillance camera and infrared sensor;

FIG. 2 shows a front view of the dumbbell shaped surveillance camera and infrared sensor of FIG. 1;

FIG. 3 shows a back view of the dumbbell shaped surveillance camera and infrared sensor of FIG. 1;

FIG. 4 shows a left view of the dumbbell shaped surveillance camera and infrared sensor of FIG. 1;

FIG. 5 shows a right view of the dumbbell shaped surveillance camera and infrared sensor of FIG. 1;

FIG. 6 shows a top view of the dumbbell shaped surveillance camera and infrared sensor of FIG. 1; and,

FIG. 7 shows a bottom view of the dumbbell shaped surveillance camera and infrared sensor of FIG. 1.

The broken lines in the drawings are shown for the purpose of illustrating portions of the dumbbell shaped surveillance camera and infrared sensor and form no part of the claimed design.

1 Claim, 7 Drawing Sheets
